ABSTRACT

A trash compactor incorporates a vertically operating ram in which, at the top of the ram's stroke, a bottom section of the ram is automatically moved horizontally rearwardly in order to expose the mouth of a trash container below. Thus the container need not be moved outside of the compactor's cabinet in order to deposit trash. Instead, trash is deposited through a door on the front of the cabinet directly into the container beneath the ram.

TRASH COMPACTOR

BACKGROUND OF THE INVENTION

The typical trash compactor, especially for domestic use, requires that the container in which the trash is compacted be pulled forwardly from under the ram and outside of the compactor's cabinet in order to expose the mouth of the container so that trash can be deposited. This requirement stems from the fact that the overall height of the compactor is limited, so that, for instance, it can be located beneath a typical kitchen counter, whence the ram at the top of the stroke is disposed so closely above the mouth of the container that trash can be deposited only after first moving the container. Of course, if there were no height limitations, the compactor could be designed so that the ram at the top of its stroke is sufficiently above the container's mouth to allow deposit of trash without need to move the container. Even within the height limitations, the container could be made relatively shallow and the ram short so that at the top of its stroke there is a sufficient gap between the ram and the container's mouth through which trash can be inserted. But that design is not acceptable since it too severely limits the amount of trash the container can hold before it must be emptied. Hence the chief object of the present invention is a trash compactor of countertop height, having acceptable trash capacity, in which the container need not be moved outside of the compactor's cabinet in order to deposit trash.

SUMMARY OF THE INVENTION

Essentially, in its preferred form the present invention employs a vertically acting ram split into upper and lower sections, the latter section being slidably movable on ways horizontally rearwardly with respect to the upper section. At the top of the ram's stroke its lower section is in its rearward position so that the mouth of the trash container below is exposed for deposit of trash through a relatively small door in the front of the compactor's cabinet. The ram is operated by a motor driven screw and at the beginning of its descent, an arrangement of pinion and rack gears rapidly moves the lower section of the ram forwardly into alignment with the upper section and the mouth of the container so that the ram can enter the container as it descends to compact the trash. The ram is automatically reversed at the bottom of its stroke and as it emerges from the mouth of the container, the pinion and rack gears act to move the lower section of the ram rearwardly again to expose the mouth of the container. The latter is carried on a slide-out mount so that it can be pulled forwardly from the cabinet and removed for emptying. Until the latter is needed, however, and unlike most current trash compactors, the container remains within the cabinet, loading being accomplished simply by opening the door on the front of the cabinet which is preferably hinged along its bottom edge so that when open it forms a chute-like entrance for the trash to direct it into the container.

BRIEF DESCRIPTION OF THE DRAWINGS

FIG. 1 is a vertical section through a trash compactor according to the invention illustrating the ram at the top of its stroke and its lower portion moved rearwardly to expose the mouth of the container below, the section being taken just inboard of a side wall of the cabinet,

certain additional parts being further shown in section taken along the line 1—1 of FIG. 2.

FIG. 2 is a horizontal section taken along the line 2—2 of FIG. 1 but showing the lower portion of the ram in its forward position in alignment with the upper portion and the mouth of the container.

FIG. 3 is a partial rear elevational view, also partly in section, taken along the line 3—3 of FIG. 1.

FIG. 4 is an exploded view illustrating the mechanisms for moving the entire ram vertically and the lower ram portion to and fro horizontally relative to the upper portion.

DESCRIPTION OF THE PREFERRED EMBODIMENT

The trash compactor consists of a chassis 10 formed essentially of a heavy, downwardly flanged rectangular floor plate 11 reinforced beneath by a transverse channel assembly 12. Just inboard of and along the side edges of the floor plate 11 are located two broad, shallow vertical channels 13 disposed in facing relation to each other only one being illustrated in FIG. 1. The lower ends of the channels 13 are provided with horizontal tongues 13a which pass through slots 11a along the side flanges of the floor plate 11 and engage its under face, being secured thereto by bolts 13b. The channels 13 extend nearly to the top of the compactor and are capped by a heavy, downwardly flanged top plate 14, also reinforced above by a pair of transverse channel assemblies 15. The respective opposite flanges of the vertical channels 13 are connected by horizontal cross-plates 16 just below the top plate 14, all to form in effect a heavy, cage-like structure in which the ram operates. Over the chassis 10 is slipped an open front, rectangular sheet metal cabinet 17 whose forward edges are flanged at 17a and provided with a toe space 18. The front of the cabinet is closed by three panels 19, 20, and 21 against the cabinet flanges 17a, the upper edges of the panels 20 and 21 being provided with hand grips 22 and 23, while the panel 20 is hinged at 24 at its lower corners to the side walls of the cabinet 17 to provide a trash loading door. The cabinet 17 is secured only to the rear and side edges of the floor plate 11, being otherwise spaced from the chassis 10 in order to minimize transmission of vibration.

The ram assembly, generally indicated at 30, consists of an upper horizontal plate 31 of rectangular shape generally spanning the area bounded by the four inner corners of the channels 13 and provided with a pair of transverse upwardly turned flanges 32. From the side edges of the plate 31 depend a pair of deep skirt plates 33 (only one being illustrated in FIG. 1), reinforced by angle braces 34 about the two edges of the plate 31 between the skirt plates 33 and by flanges 35a and 35b along the four vertical and two bottom edges of the skirt plates 33. Over the four corners formed by the skirt plates 33 and their flanges 35a are secured glides 36 fashioned from flat strips of nylon which slidably bear against the inner corners of the channels 13. Centrally beneath the upper plate 31 are welded the upper ends of a pair of vertical supports 37, somewhat V-shaped in cross section, their respective ends 37a being located in spaced, opposed relation to each other adjacent the front and rear edges of the plate 31. Welded to the lower ends of the supports 37 is a circular lower end plate 38, centrally disposed with respect to the upper plate 31, which is provided with a pair of spaced,

parallel slots 39 (see FIG. 4) between the support ends 37a and extending perpendicular to the cross-plates 16 from the rear edge of the plate 38 forward to abreast of its center. The slots 39 in turn receive a pair of T-shaped ways 40, to whose upper faces is secured a pair of rack gears 41 and to whose lower ends faces is screwed a circular upper end plate 42, substantially congruent with plate 38, whose upper face is in sliding contact with the lower face of plate 38. To the lower face of the plate 42 are welded the upper ends of a second pair of vertical supports 43, similar to the supports 37 and similarly disposed, to whose lower ends is welded a circular ram head supporting plate 44. Below the latter is releasably attached a circular ram head 45. Hence the upper end plate 42, the supports 43, the support plate 44 and the ram head 45 are suspended by the ways 40 and together with the rack gears 41 form a lower ram section 46 which is slidable as a unit in the slots 39 from a forward position in which it is vertically aligned with the upper ram section 47 to a rearward position as shown in FIG. 1.

The mechanism for moving the lower ram section 46 relative to the upper section 47 consists of a pair of spaced pinion gears 50 fixed intermediate the ends of a horizontal shaft 51 extending between the rear walls of the supports 37 and journaled therein at 52, the pinion gears 50 operatively engaging and driving respective rack gears 41. To the shaft 51 between the pinion gears 50 is also fixed a drive pinion gear 53 which is engaged by a vertical rack gear 54 at the lower end of a vertical support 55 extending through an aperture 56 in the upper ram plate 31 and welded at its upper end to the underside of the chassis top plate 14. Hence, when the ram assembly 30 is at the top of its stroke and the lower ram section 46 is in its rearward location, all as shown in FIG. 1, initial downward movement of the ram assembly 30 will cause the rack gear 54 to drive the pinion gears 53 and 50 and thus the rack gears 41, whence the lower ram section 46 will slide forwardly on the ways 40 into alignment with the upper ram section 47 by the time the pinion gear 53 has disengaged from the lower end of the rack gear 54. In reverse, as the ram assembly 30 approaches the top of its stroke, the pinion gear 53 will be reengaged by the rack gear 54 and the lower ram assembly 46 will thus have slid to its rearward position by the time the ram assembly 30 halts at the top of its stroke.

A separate mechanism drives the entire ram assembly 30 vertically. For this purpose the upper ram plate 31 is centrally apertured at 60 between the supports 37 to receive a flanged swivel seat 61 for a swivel nut 62 having a squared upper boss, the seat 61 and nut 62 being retained by a flange plate 63 bolted through the plate 31. The flange plate 63 has a squared aperture receiving the squared boss of the swivel nut 62 in order to prevent its rotation. Through the swivel nut 62 is threaded a long, Acme type vertical screw 64, its threads being interrupted at 65 toward its upper end and provided thereabove with a pair of opposite drive flats 66, the screw 64 extending down through an aperture 67 in the lower end plate 38 and an elongated slot 68 in the upper end plate 42, the slot 68 extending from the center of the plate 42 and opening through its forward edge in order to accommodate the movement of the lower ram section 46 relative to the upper section 47. The upper end of the screw 64 is retained in and driven by an appropriate gear box 69 secured to the un-

derside of the chassis top plate 14, the entire ram assembly 30 thus being suspended from the gearbox 69. A drive shaft 70 extends rearwardly from the gear box 69, the shaft 70 being supported by a pillow block 71 adjacent its rear end and secured to the underside of the chassis top plate 14. The rear end of the shaft 70 is fitted with a V-pulley 72 which is engaged by a V-belt 73 driven by a V-pulley 74 therebelow on the shaft of an appropriate electric motor M carried by a bracket 75 also secured to the underside of the chassis top plate 14.

Accordingly, as the screw 64 is driven in the appropriate direction, the entire ram assembly 30 moves from its uppermost or withdrawn position downwardly owing to the swivel nut 62. During the initial portion of its travel the lower ram section 46 moves forwardly into alignment with the upper section 47 in the manner previously described. The eight nylon glides 36, which in effect provide a total of eight bearing faces, fit tightly against the inner corners of the chassis channels 13 and are heavily greased. The screw 64, which provides a single axis of thrust centrally disposed with respect to the ram assembly 30 and parallel to the glides 36, absorbs most of the resistance encountered by the ram assembly 30 as it descends. Any tendency for it to "cock" or "twist" is resisted by the strength of the assembly 30, the extensive length of the eight surfaces of the nylon glides 36 and the substantial lateral spacing of the latter from the axis of the screw 64. Any "cocking" relative to the screw 64 is accommodated by the swivel seat 61 and nut 62. The interrupted thread portion 65 of the screw 64 prevents over-travel of the ram assembly 30 upon its upward movement from its lowermost or compacting position.

The slide-out mount 80 for the trash container is formed by a rectangular floor pan 81 having a large centrally located, circular aperture 82 therein normally axially aligned with the screw 64. The mount 80 is carried on a pair of three-piece, ball bearing full extension glides (not shown) connected to the channels 13 and the floor pan 81. A pair of upright, trapezoidal braces 83 (only one being shown) secures the side edges of the floor pan 81 to the side edges of the cabinet front panel 21. The cylindrical trash container 84 is supported in the aperture 82 above the floor plate 11 by means of several leaf springs (not shown) carried by the floor pan 81. When the ram 30 is in its fully retracted position, the container 84 can be pulled forwardly out of the cabinet 17 on its mount 80, as indicated by the arrow in FIG. 1, by the hand grip 23 in order for trash to be emptied. Until that is necessary the container 84 remains within the cabinet 17, trash being deposited through the door 20 since the mouth of the container is exposed owing to the rearward location of the lower ram section 46 as shown in FIG. 1. When the door 20 is opened with the hand grip 22 it provides a chute-like incline to direct trash into the container 84. The door 20 may include suitable stops (not shown) for this purpose.

The ram assembly 30 is activated by any conventional means (not shown) controlling forward and reverse operation of the motor M. It first descends to compress the trash at which time the container supporting springs deflect allowing the container 84 to sink through the aperture 82 until its bottom sits firmly upon the chassis floor plate 11. When maximum compression has been reached, the motor M is automati-

cally reversed by any of well-known means (not shown) to withdraw the ram assembly 30. It will be understood, of course, that the diameters of the pinion gears 50 and 53 and the length of the rack gear 54 must be appropriately chosen so that the lower ram section 46 is moved rearwardly and forwardly, as the case may be, only when the ram head 45 is above the mouth of the container 84, that is to say, as previously pointed out, at the end and the beginning, respectively, of the stroke of the ram assembly 30. Preferably, the door 20, as well as the mount 80, also incorporate suitable safety interlocks (not shown) so that the motor M is automatically halted if either is opened during the compacting operation.

Though the invention has been described in terms of a particular embodiment, being the best mode known of carrying out the invention, it is not limited to that embodiment alone. Instead, the following claims are to be read as including all adaptations and modifications of the invention falling within its spirit and scope.

I claim:

1. In a trash compactor having a cabinet containing a chassis, a trash container and a ram assembly including a ram head, the ram assembly being linearly movable relative to the chassis in a compacting stroke from a withdrawn position above the trash container, the trash container being disposable in aligned relation closely below the ram head, downwardly to a compacting position inside the container and then in a withdrawal stroke back to its withdrawn position, the improvement wherein the ram assembly includes an upper portion and a lower portion to which the ram head is attached, the lower ram portion being laterally movable within the confines of the cabinet relative to the upper ram portion and the container into and out of said alignment with the container when the ram head is above the container effective to expose the mouth of the container for deposit of trash therein through an access opening in the cabinet; and wherein said lateral movement is achieved by transfer means which automatically moves the lower ram portion out of said alignment near the end of the ram assembly's withdrawal stroke and moves the lower ram portion back into said alignment at the beginning of the ram assembly's compacting stroke when the ram head is above the container in each case, the transfer means being activated by said linear movement of the ram assembly

and comprising driven means carried by the upper and lower ram portions and drive means carried by the chassis and operative upon the driven means only during said linear movement of the ram assembly when the ram head is above the container.

5 2. The compactor of claim 1 wherein the driven means comprise first gear means carried by the lower ram portion and second gear means carried by the upper ram portion and operatively engaging the first gear means, and wherein the drive means comprises third gear means carried by the chassis and operatively engaging the second gear means.

3. The compactor of claim 2 wherein the upper and lower ram portions are joined by a pair of upper and lower plate members respectively secured to said ram portions, the plate members having laterally extending mating faces therebetween and interlocking guide means securing the lower to the upper ram portion, the guide means extending parallel to the direction of said lateral movement of the lower ram portion, the lower plate member being laterally slidable relative to the upper plate member over said faces and along the guide means to provide for said lateral movement of the lower ram portion.

15 20 4. The compactor of claim 3 wherein the guide means comprise a pair of laterally spaced rectilinear ways secured to the lower plate member and extending upwardly through the top face of the upper plate member, and wherein the first gear means are carried by the guide means above the upper plate members.

5. The compactor of claim 4 wherein the first gear means comprise a pair of rack gears secured to and parallel with said ways, wherein the second gear means comprise a pair of pinion gears operatively engaged with the rack gears, the pinion gears being fixed to a shaft journaled in the upper ram portion above and perpendicular to the rack gears, and wherein the third gear means comprise a drive pinion gear fixed to the shaft and a drive rack gear fixed to the chassis, the drive rack gear being positioned to operatively engage the drive pinion gear only when the ram head is above the container effective to cause said lateral movement of the lower ram portion into and out of said alignment near the beginning of the compacting stroke and the end of the withdrawal stroke, respectively, of the ram assembly.
